UNITED STATES PATENT OFFICE.

ARTHUR C. VAN KIRK, OF TIFFIN, OHIO.

CUFF-HOLDER.

SPECIFICATION forming part of Letters Patent No. 769,365, dated September 6, 1904.

Application filed October 14, 1903. Serial No. 177,062. (No model.)

To all whom it may concern:

Be it known that I, ARTHUR C. VAN KIRK, a citizen of the United States, residing at Tiffin, in the county of Seneca and State of Ohio, have 5 invented a new and useful Cuff-Holder, of which the following is a specification.

This invention relates to cuff-holders; and one of the objects thereof is to provide a cheap, durable, and efficient construction of cuff-holder which will be capable of firmly securing the cuff to the coat-sleeve and without marring the sleeve in any manner.

Further objects and advantages of this invention will appear in the following description, and the novel features thereof will be particularly pointed out in the appended claims, it being understood that changes in the form, proportion, and the minor details of construction may be resorted to without departing 20 from the spirit or sacrificing any of the advantages of this invention.

In the drawings, Figure 1 is a perspective view of the invention applied. Fig. 2 is a view in elevation of the invention. Fig. 3 is 25 a sectional view on the line 3 3 of Fig. 2, and Fig. 4 is a perspective view of the device.

The cuff-holder is constructed from a single piece of spring-steel bent adjacent to its longitudinal center and folded back upon itself 30 to produce a primary rigid arm 1 and a secondary spring-arm 2, said arms being substantially parallel. The primary arm 1 is provided at its outer end with a right-angular extension 3, having a hooked-shaped terminal 35 4, carrying at its extremity a flattened portion or head 5, between which and the arm 2 the cloth is clamped. The secondary spring-arm 2 is provided with an opening 6, designed to register with the head 5, whereby the latter when brought into clamping engagement with the garment will force the material thereof into the opening sufficiently to insure a firm hold of the holder being had upon the garment, but at the same time insufficient to mar the cloth.

The cuff is engaged at the proper point by a spring-clip disposed adjacent to the inner side

of the folded end of the holder-arms, said clip consisting of a pair of spring-fingers 7 8 substantially in line with the sleeve-engaging terminals of the arms and formed integral with the latter, the finger 7 being formed upon and projecting directly from one side of arm 1, while the finger 8 is formed at the opposite side of said arm and folded back upon itself and upon the inner side of the arms to overlie and coöperate with finger 7 for clamping the cuff. It may here be said that owing to the finger 8 extending over the face of arm 1 the point of engagement of the holder with the cuff 60 will when the latter is in position between the fingers be substantially in line with the point of engagement of the holder with the coat-sleeve, thereby obviating liability of the cuff in its movements exerting a lateral strain 65 upon the holder sufficient to cause its disengagement from either of the parts.

From the foregoing it is apparent that I produce a simple inexpensive device which in its entirety is constructed from a single 70 piece of metal and one which in practice may be readily engaged with the cuff and sleeve and securely hold said parts.

I claim—

A cuff-holder comprising a length of spring 75 metal folded upon itself adjacent to its longitudinal center to produce a primary arm and a secondary substantially parallel spring-arm, said arms being provided adjacent to their outer ends with coöperating garment-engaging means, and a pair of coöperating cuff-engaging fingers formed integral with one of said arms adjacent to the inner side of the folded end of the arms, one of the fingers being folded upon itself on said inner side to overlie the 85 other.

In testimony that I claim the foregoing as my own I have hereto affixed my signature in the presence of two witnesses.

ARTHUR C. VAN KIRK.
